UNITED STATES PATENT OFFICE

CHARLES W. BAKER, OF LAKE CHARLES PARK, MISSOURI

BURIAL APPARATUS

Application filed January 28, 1928. Serial No. 250,206.

My invention relates to improvements in burial apparatus and one of its objects is to provide a secure and level platform over an open grave, to make the grave more accessible; a second object is that of securing a substantially level supporting means for a mechanical coffin-lowering device; a third and very desirable object is that of providing a place for pall bearers to walk without treading on a closely adjacent grave and providing safe footing for pall bearers where monuments or other structures are close to the open grave. A further object is the provision of a coffin-lowering apparatus having grave coverings both to conceal the mouth of the grave before the introduction of the boxed casket into the grave, and to cover the mouth of the grave as the boxed casket is lowered beneath the plane of the mouth of the grave.

In order to accomplish my objects I provide two scaffold elements of adjustable length which border the long sides of the grave. These I support on end beams consisting of angle irons slidably arranged so as to accommodate graves of different widths. Each of the two end beams is supported by two leg members also composed of angle irons forming corner columns or legs. These legs are arranged so that the effective length of each may be varied to suit slopes or irregularities of the ground surface where the grave is located and this is accomplished by letting them project into the grave whereby the leveling of the platform is accomplished. This arrangement also precludes any lateral sliding when the platform is loaded. To support the legs at the desired height and to hold them secure against the sides of the grave I provide two spreaders which are arranged to spread the legs laterally. A spreader is placed under each of the beams above mentioned and at ground level. These spreaders act as the supporting connection with the ground and it is convenient to provide footings of timber such as the battens shown which may be disposed in any convenient manner. In order to assure stability for the system I provide a special connecting block for the junctions of the beams and the legs. These blocks are recessed at right angles and act to maintain such angle

when the engagement screw is tightened but to afford a revoluble connection when this screw is loosened, whereby the beam and legs may be swung into right line and thus occupy a minimum of space when not in use.

The covering of the grave opening at two successive stages of the interment is effected by two pairs of sheets of artificial grass fabric, successively operated to conceal the mouth of the grave before the introduction of the boxed casket, and at the stage when said casket has been lowered to a point beneath the plane of the mouth of the grave.

Another object of my invention is to mount the covering apparatus within the casket lowering apparatus in order that the grave will not need any special excavation for the purpose of accommodating the covering apparatus. My entire apparatus is to be mounted and operated upon a grave prepared in the ordinary manner, and with the ordinary dimensions, and without any special excavation for the purpose of accommodating any part of my apparatus.

Drawings

Fig. 1 is a perspective view of an apparatus embodying my invention.

Fig. 2 is a side elevation of my leveling device set upon sloping ground and leveled. In this view the spreaders are shown resting upon battens.

Fig. 3 shows an end elevation of my leveling device; in this view there is indicated in dotted lines my casket-lowering device.

Fig. 4 shows a detail of a clamp employed to connect and secure the two elements of the horizontal beams and provide adjustability for different widths of graves, in my leveling device.

Fig. 5 shows a detail of a corner connection between the beams and legs of my leveling device.

Fig. 6 is another view of the same corner connection.

Fig. 7 is a detail of the block connecting this same beam to the leg.

Figs. 8 and 9 form a broken view of the spreader of my leveling device.

Figs. 10 and 11 form a broken view in elevation of the same spreader.

Fig. 12 shows one convenient form of batten.

Fig. 13 is a plan view of a leveling device embodying my invention.

Fig. 14 is a transverse mid-sectional view of the apparatus shown in Fig. 1, with a boxed casket in place before lowering into the grave, taken on the plane 15—15 of Fig. 2.

Fig. 15 is a like view, the casket shown when lowered beneath the plane of the mouth of the grave.

Figs. 16, 17 and 18 are detailed views of the 15 trip mechanism employed in lowering the upper pair of grass curtains.

Description

As shown in the drawings, I employ two 20 extensible scaffold members A—A shown in plan in Fig. 14. Slides 11 serve to secure each of said elements A in alinement and in the desired extended position. The scaffold elements A—A are secured together by means 25 of the extensible end beams B—B; each of said beams B is supported on a pair of vertical legs C to which the beam B is removably attached by means of the bolt 12 and nut 13, and the clamp 18, said clamp 18 being so formed as to comprehend both the leg and the beam each within a confining space (see Figs. 5, 6 and 7).

Each of the beams B is composed of the two angle irons 14—15 which are adjustably 35 secured together by means of the clamp 16 and set screw 17, which clamp 16 is shown in detail in Fig. 4.

Battens D of any convenient superficial form are laid upon the ground in contact with 40 the legs C, as shown in Figs. 1, 2 and 3, and the spreaders E, at each end of the framework, rest upon or near the upper surface of said battens D. Each of said legs C has a vertical series of perforations 19, and each of 45 said spreaders E has a pair of plungers 20—20 arranged to be seated in said perforations 19. Said plungers 20 are operated by means of levers 21 fulcrumed at 22 to standards 23. Hooks 24, mounted as shown in Figs. 8 and 50 9, provide slots 25 to engage said legs C and permit the spreader E to be located at the desired height by means of its plungers 20.

As shown in Figs. 8, 9, 10 and 11, the spreader E is composed of the overlapping bars 26 and 27 secured together by the slides 55 28—28. Fig. 8 shows its plunger 20 in closed position; Fig. 9 shows said plunger 20 and slot 25 in opened position.

The apparatus thus disclosed is adapted to the reception of a casket-lowering device F, such as illustrated in dotted lines in Fig. 3 and which is to rest in approximately horizontal position upon the scaffold members A—A.

My described apparatus, as used upon and

over a hillside grave, is illustrated in Fig. 2, showing how the approximately horizontal position of the scaffold members A—A are secured under such conditions of surface inclination.

The interment having been completed the apparatus, by reason of its described detail construction, is reduced to its elements and the scaffold members A—A are reduced to their shortest length by the telescoping of each of said members; all with the result that the entire apparatus may be removed and stored within the smallest possible limitations of space.

To secure rigidity of the assembled frame I provide the bolt 30 which extends through the leg C and through two of the slats composing the scaffold member A and is held in place by the winged nut 31.

The leveling apparatus thus described being in place about the mouth of a grave, a casket-lowering apparatus F comprising side rollers 40 and end rollers 41, geared together at their meeting ends by the beveled gear 42, and actuated by the crank handle 43, is deposited in place upon the leveling apparatus as shown in Fig. 1. Lowering straps 44 are mounted upon the rollers 40—40, the straps 44 receiving the casket G for the purpose of lowering into the grave, as illustrated in Figs. 15 and 16. This lowering apparatus is old in the art and constitutes but one element of my burial apparatus.

Mounted upon the scaffold members A—A, at each of the four corners of the grave, I provide an angle bracket H having a vertical flange 45 and a horizontal flange 46 carried in the strap member 47, which terminates in the depending lip 48, as shown in Fig. 19. The tubular rod 49 is secured to the flange 45 by the bolt 50, which is mounted through the perforation 51. Two projecting humps 52—53 are formed in the flange 45, to hold the tubular rod 49 alternately in vertical and in horizontal position as indicated in Fig. 17. In the open mouth of the tubular rod 49 I provide a T-bar I having the stem 54 and cross bar 55 as shown in Fig. 18; the stem 54 is adjustably secured in place within the tubular rod 49 by means of the thumb screw 56. Between each pair of T-bars I is mounted a telescopic rod 57 (see Fig. 1). The purpose of the telescopic rods 57 is to hold a sheet of grass fabric J as shown in Fig. 1.

Hingedly adapted to the flange 46 is the bar 58, attached to the flange 46 by means of the bolt 59, which bolt 59 is mounted in the perforation 60 in said flange 46 (see Figs. 17 and 19). The flange 46 is provided with the humps 61—62 which engage with the bar 58 to hold said bar 58 alternately in horizontal and depending vertical positions, as shown in 17. Between each pair of the bars 58 a telescopic tubular rod 63 is mounted by means of angle irons 64 which are adjustably mount-

ed in the tubular bar 58 by means of thumb screws 65.

The apparatus being assembled and installed as shown in Figs. 1 and 15, a pair of sheets of grass fabric K is mounted to cover the scaffold members A—A, and secured thereon by tacks or other fastening members 66, the inner edges of said sheets K extending over the rods 63—63, and extending downwardly into the grave L as shown in Fig. 15. The casket G is then placed in position on lowering straps 44—44 as shown in Fig. 15 and the casket being lowered contacts with the tubular rods 63—63, depressing the same and forcing said rods 63—63 and the grass fabric sheets K—K carried thereby into the grave, in the manner shown in Fig. 16.

The bar 58 and rod 49 are connected together by appropriate elastic and removable mechanism illustrated herein as the elastic link M, which comprises a cylinder 67 and rod 68. The cylinder 67 is mounted on the bar 58 by means of a band 69. The rod 68 is mounted through a perforated cap 70, which cap 70 is mounted on the free end of cylinder 67. At its lower end the rod 68 is provided with a head 71 sliding freely within cylinder 67. At its upper end the rod 68 is provided with an enlarged head 72, which head 72 is adapted to fit into the aperture 73 formed in the wall of the tubular rod 49 (see Figs. 17 and 18). Between the head 71 and the inner face of the cap 70, I provide a coiled spring 74, to render the link M measurably elastic.

As the casket G descends from the position shown in Fig. 15 to that shown in Fig. 16, as the rods 63—63 are depressed, they draw after them, by reason of the link M, the rods 49—49 and the grass fabric sheets J—J, which immediately serve to form a covering for the mouth of the grave in the manner shown in Fig. 16.

The interment having reached the stage where the casket G is in place at the bottom of the grave, the grass sheets J—J are removed and the rods 49 and bars 58 are disconnected by the removal of the enlarged head 72 from the slot 73 permitting the disengagement of the link end.

The straps 44—44 are disconnected at either or both ends from the rollers 40 and withdrawn from the grave L in the usual manner. The entire apparatus is then in condition for removal.

I am aware that various grave-covering devices have been employed in concealing the mouth of a grave during the process of interment; the novelty of my apparatus resides, inter alia, in providing two two-parts sets (upper and lower) of fabric-cover holding frames, adjustable as to the length and breadth of the grave; and an elastic and detachable connection between said upper and lower frames; the entire covering mechanism

being mounted within the casket-lowering mechanism; the entire covering mechanism requiring no additional excavation of the grave to accommodate it. Furthermore, the elasticity of the connection between the upper and lower fabric-holding frames enables the upper frame to clear any height of casket wherewith said covering apparatus may be employed, this being a valuable function in view of the varying height of caskets of the same length and width.

Various changes of structure of the several parts of my apparatus may be accomplished without departure from my actual invention as defined in the appended claims.

I claim:

1. In a burial apparatus a covering mechanism comprising an upper two-part fabric cover holding frame; a lower two-part fabric cover holding frame; an elastic and detachable connection between said upper and lower frames; and a casket-lowering apparatus arranged by the lowering of a casket to successively actuate said upper and lower holding frames.

2. In a burial apparatus a covering mechanism comprising an upper two-part fabric cover holding frame; a lower two-part fabric cover holding frame, each of said frames being adjustable as to length and width; an elastic and detachable connection between said upper and lower frames; and a casket-lowering apparatus arranged by the lowering of a casket to successively actuate said upper and lower holding frames.

3. In a burial apparatus a covering mechanism comprising an upper two-part fabric cover holding frame; a lower two-part fabric cover holding frame, each of said frames being adjustable as to length and width; an elastic and detachable connection between said upper and lower frames; and a casket-lowering apparatus arranged by the lowering of a casket to successively actuate said upper and lower holding frames, said covering mechanism being mounted and operable within the casket-lowering apparatus.

In testimony whereof I have hereunto affixed my signature.

CHARLES W. BAKER.
